DROP PIT APPARATUS

Hugh K. Christie, Harvey, Ill., assignor to Whiting Corporation, Harvey, Ill., a corporation of Illinois

Application November 21, 1938, Serial No. 241,588

15 Claims. (Cl. 104—32)

The invention relates to drop pit apparatus for handling wheels and trucks of railway equipment.

In drop pit apparatus for railway equipment which comprises a compound drop table or one which is composed of sections for dropping either a single pair of wheels of a truck or for dropping a complete truck, it has heretofore been necessary to provide at least three pairs of rail-sections to bridge the pit. In practice it is desirable to reduce the number of rail-sections and joints required for this purpose.

One object of the invention is to provide an improved compound pit-bridging table which eliminates the necessity of more than two pairs of rail-sections. This object is accomplished primarily by providing a table which comprises a main section provided with beams for completely spanning the pit and an auxiliary table-section which fits into an open-ended space formed in one end of the main-section and is adapted to be supported jointly from one side of the pit and from the table and meeting rail-sections on the table-sections, the rail-sections on the auxiliary section terminating at one side of the pit.

Another object of the invention is to provide a compound table of this type, which comprises an auxiliary section which is conterminous with the side-beams of the main-section which extend completely across the pit, so that when a pair of wheels has been lowered and transferred and lifted to an adjoining track, it can be wheeled directly from said section onto a track of the roundhouse.

Another object of the invention is to provide a compound table in which the auxiliary section for dropping a single pair of wheels extends between the main table-section and the pit and is supported partly from the pit-wall and partly from the main-section of the table.

Another object of the invention is to provide improved means for selectively lifting one of the table-sections above track-level when a single pair of wheels is to be disconnected from the truck. This object is obtained by providing engaging elements between the lifting carriage and the table-sections whereby the lifting mechanism, which is controlled by the relative positions of the carriage under the table, will unitarily lift both sections of the table above track level when a truck is to be uncoupled from the locomotive, and shift only one table-section above track-level for uncoupling a single pair of wheels. By utilizing the movement of the lifting carriage in the pit for this purpose, lifting blocks which are

movably connected to either the carriage or the table, are dispensed with.

Other objects of the invention will appear from the detailed description.

The invention consists in the several novel features which are hereinafter set forth and are more particularly defined by claims at the conclusion hereof.

In the drawings:

Fig. 1 is a plan of a drop-pit apparatus embodying the invention, parts being broken away for illustrative purposes. Fig. 2 is a perspective of the drop-table in track-bridging position. Fig. 3 is a perspective of the lifting carriage. Fig. 4 is a longitudinal section of the drop pit apparatus in the pit, parts being shown in elevation. Fig. 5 is a section illustrating the gearing for operating the lifting-screws to raise and lower the lifting-carriage for the table. Fig. 6 is a section on line 6—6 of Fig. 4. Fig. 7 is an end view of the drop-table illustrating the auxiliary table-section raised above track-level by the lifting mechanism. Fig. 8 is a perspective of the auxiliary table-section, the flooring being omitted.

The invention is exemplified with a shop installation which usually comprises a series of tracks arranged in any suitable manner on the shop floor with rails *b* terminating at the sides of a pit *a*, which intersects the floor-tracks, a drop-table structure adapted to be raised or lowered in the pit and composed of sections *c* and *d*, and a carriage *f* for conjointly raising or lowering both table-sections or independently raising or lowering the table-section *d*.

The main table-section *c* comprises a pair of longitudinal I-beams *10* at its sides and extending entirely across the pit; a cross I-beam *11* rigidly connecting the beams *10* at one end of table-section *c*; and a cross I-beam *12* fixed to and rigidly connecting beams *10* at a point spaced some distance inwardly of the other end of table-section *c*. The beams *10* extend entirely across the pit so that table-section *c* can be releasably supported directly from the pit-walls. The beam *12* is spaced from one side of the pit to leave an open-ended space between beams *10*, beam *12* and one side-wall of the pit, in which table-section *d* fits. Longitudinal I-beams *c'* are secured to and extend between cross-beams *11* and *12* of table-section *c* to support rail-sections *c''* which terminate at the outer sides of beams *11* and *12* and extend completely over the area between the outer sides of said beams. A floor *c³* may be provided to cover the spaces between the beams of the table-section *c*. Table-section

c is releasably supported from the pit-walls by four bolts *13* which are slidably mounted in fixed guides *14* adjacent the outer ends of beams *10*. The outer ends of bolts *13* are shiftable to engage I-beams *e* which are built into the pit-walls. A hand-lever *15* at one side of table-section *c* is fixed to a transverse shaft *16* which is journaled in beams *10* for simultaneously shifting all of the locking bolts *13*. Oppositely extending arms *17* on shaft *16* at the outer sides of beams *10*, are connected by links *18* to bolts *13*. When the lever *15* is in position illustrated in Fig. 1, the projecting ends of bolts *13* will rest on the beams *e* and support the beams *10* and the table-section *c* in track-bridging position from the pit-walls. When the lever is shifted to withdraw the bolts *13* from engagement with beams *e* the table-section *c* will be supported on and will be released so it can be raised by the lifting carriage.

The auxiliary table-section *d* is rectangular and fits in the open-ended space between beams *10* and cross-beam *12* of table-section *c* and its outer end extends to the adjacent side-wall of the pit, to form a table-section upon which one pair of wheels of a truck is adapted to be spotted so that that pair of wheels can be raised or lowered independently of the other wheels on the locomotive or truck. The outer end of the table-section *d* is substantially conterminous with the adjacent ends of the beams *10* of table-section *c*. Table-section *d* comprises channeled side-beams *19*, a cross-beam *20* at its outer end, and a cross-beam *21* at its inner end, which are secured together to provide a rigid rectangular frame-structure. Longitudinal I-beams *22* are fixed to, and extend between, cross-beams *20* and *21* to support rail-sections *d'* which extend from end to end of table-section *d*. A floor *d²* is laid over beams *19*, *20* and *21* between beams *10* of table-section *d*. A pair of bolts *25* are slidably mounted in guides *26* fixed to beams *22* and are adapted to project from the outer end of table-section *d* to engage the beam *e* in one of the pit-walls to support table-section *d* from the pit. A pair of bolts *27* are slidably mounted in guides fixed adjacent the inner ends of beams *22* to support the inner end of table-section *d* from the cross-beam *12* of table-section *c*. A hand-lever *28* is fixed to a shaft *29* which is journaled in the beams *19* and is provided with oppositely extending arms *30* which are connected by links *31* to bolts *25* and *27*, respectively. When the lever *28* is shifted to project the bolts *25*, *27*, bolts *25* will engage beam *e* in one wall of the pit and bolts *27* will engage cross-beam *12* of table-section *c* so that table-section *d* will be supported partly by the pit-wall and partly by the table-section *c*.

A characteristic of the table-structure described is that the table-section *c* comprises beams which are adapted to extend completely across the pit and an end-portion which carries rail-sections *c²* which extend from one end of table-section *d* to the meeting end of table-section *d*. Table-section *d* is of sufficient area to support one or more pairs of wheels of a truck or a locomotive. The table-section *d* is adapted to support one pair of wheels and is provided with rail-sections *d'* which extend from the meeting line of the inner ends of the table-sections to the other side of the pit so that the table requires only two pairs of rail-sections with a single joint between them for spanning the pit or the rail-sections *b* of the shop. When the table-section *d* is unlocked from table-section *c* and both sec-

tions are unlocked from the pit, they can be jointly raised and lowered by the lifting mechanism to raise and lower all of the wheels on both sections of the table. When table-section *c* is locked to the pit and table-section *d* is unlocked from the pit and table-section *c*, it can be raised or lowered independently of section *c* to raise or lower a single pair of wheels spotted on section *d*.

The lifting mechanism comprises the vertically movable carriage *f* which is built up of longitudinal I-beams *34*, a pair of channeled cross-beams *35* at one end, and a pair of cross-beams *36* at the other end, of the carriage, and a cross-beam *37*, all rigidly secured together. The cross-beams of each of said pairs are fixedly secured together and spaced apart by saddles *38*. The mechanism for raising and lowering carriage *f* comprises a series of four vertical screws *40* which are threaded to nuts *41*, upon which the saddles *38* of carriage *f* are supported. These screws are mounted upon a trolley *g* which is provided with wheels *g'* adapted to travel on rails *g²* on the bottom of the pit. Each screw *40* is supported in a gear-case *42* which is supported on the trolley. The upper end of each screw *40* is journaled in a bearing *40^a* in the upper end of one of the channeled guide-posts *f²* which are fixedly secured to the gear-cases *42*, respectively. The outer ends of the cross-beams *35*, *36* extend into the channels of said posts to guide the carriage *f* vertically. A gear *43* is fixed to the lower end of each screw *40*, and a pinion *44* meshes with, and is adapted to drive, each gear *43*. The pinions *44* in the gear-case *42* at one side of the trolley are driven by a shaft *45* which is driven from an electric motor *46* through suitable reduction gearing *47*. Gears *43* at the other side of the trolley are each driven by a cross-shaft *48* provided with pinions *49* meshing, respectively, with the gears *43* on the opposite sides of the trolley. This provides gearing for simultaneously rotating the screws *40* for rectilinearly raising and lowering the lifting carriage *f*.

In practice, it is desirable to provide for selectively lifting above track-level both table-sections, for uncoupling a truck or plurality of wheels, or the table-section *d* independently, for uncoupling a single pair of wheels.

For the purpose of lifting both sections, cross-beams *35* at one end of lifting-carriage *f*, are adapted to engage the under-face of side-beams *19* and longitudinal beams *c'* of table-section *c* and the cross-beams *36* at the other end of carriage *f* are adapted to engage the under-face of side-beams *10* and the longitudinal beams *22* of table-section *d*. One of the longitudinal beams *34* of the lifting carriage also engages one of the longitudinal beams *c'* of table-section *c* and one of the beams *22* of table-section *d*. Cross-beam *37* also engages the under-face of the inner end of beams *22* of table-section *d*.

For the purpose of raising table-section *d* above track-level independently of table-section *c*, a pair of outer blocks *50* and a pair of inner blocks *51* are fixedly secured to the top of the lifting carriage *f*. When both sections of the table are to be lifted together the trolley and lifting carriage will be shifted along the pit so blocks *50*, *51* on the lifting carriage will be out of vertical alignment with the longitudinal beams *22* of table-section *d* and beams *c'* of table-section *c*, as shown in Fig. 6, so that they will permit the lifting carriage to be raised to engage both of the table-sections for simultaneous lifting. When the table-section *d* is to be raised independently

of table-section *c* the trolley is shifted in the pit so the blocks 50, 51 at one side of the lifting carriage will engage only one of the longitudinal beams 22 and the blocks 50, 51 at the other side of the lifting carriage will abut against the other longitudinal beam 22 when the lifting-carriage is raised. As a result, when the lifting-carriage is raised while the blocks 50, 51 are operatively positioned to engage beams 22 of table-section *d*, that section will be raised above track-level, as illustrated in Fig. 7. This exemplifies a compound drop pit table with a lifting-structure, which, by being brought into different positions in the pit, may be selectively positioned to lift one or both of the table-sections above track-level. By utilizing the movement of the trolley and lifting carriage, with the lifting carriage thereon for this purpose, the necessity of providing devices which are movably connected to the table-section or lifting-carriage for that purpose, is avoided.

In order to prevent the main table section *c* from being released from the beams *e* at both sides of the pit, without first releasing the bolts 25 which engage one of the pit-beams *e*, a device is provided for preventing lever 15 and its shifting connections for bolts 13, which support table-section *c*, from being shifted to release bolts 13 from the pit-walls. This device comprises an abutment 60 supported on rods 61 which are slidably mounted in cross-beam 12 and adapted to engage the inner end of one of the bolts 27 on table-section *d*. Rods 61 are connected by a link 62 to an arm 63 which is fixed to the cross-shaft 16 to which lever 15 is fixed. When bolts 25 and 27 on table-section *d* are in their locking position, abutment 60 will be positioned to engage the inner face of one of the bolts 27, to prevent the shift of lever 15 and shaft 16 to release the locking bolts 13 for the table-section *c*. When bolts 25, 27 are in locking position, links 31, through which said bolts are shifted, are in substantially dead-center relation to shaft 29 so that said bolt 27 will prevent movement of the abutment 60. This exemplifies means for preventing the main table-section *c*, which spans the pit, from being released for lowering movement thereof without first releasing the locking bolts for the auxiliary table-section *d*. This prevents any lowering movement of the auxiliary table-section *d* until the locking bolts 25 and 27 are shifted to unlocking position so that the table-section *d* can be lowered synchronously and rectilinearly with section *c*.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a drop table, the combination of a vertically movable table-section comprising a rigid structure adapted to extend completely across the drop pit and provided with a space which is open at one end of the table and with rail sections extending from the inner end of said space to the wall at one side of the pit, an auxiliary section fitting in, and provided with rail-sections for extending across the open-ended space from its inner end to the wall at the opposite side of the pit, the auxiliary section being separable from and lowerable independently of the rigid structure and means for releasably supporting the sections in the pit.

2. In a drop table, the combination of a ver-

tically movable table-section comprising a rigid structure adapted to extend completely across a drop pit and provided with beams forming three sides of a space which is open at one end of the table and with rail sections extending from the inner end of said space to the wall at one side of the pit, a substantially rectangular auxiliary section fitting in, and provided with rail-sections for extending across the open-ended space from its inner end to the wall at the opposite side of the pit, the auxiliary section being separable from and lowerable independently of the rigid structure and means for releasably supporting the sections in the pit.

3. In a drop table, the combination of a vertically movable table-section comprising a rigid structure adapted to extend completely across a drop pit and provided with a space which is open at one end of the table and with rail-sections extending from the inner end of said space to the wall at one side of the pit, an auxiliary section fitting in, and provided with rail-sections for extending across the open-ended space from its inner end to the wall at the opposite side of the pit, the auxiliary section being separable from and lowerable independently of the rigid structure, means for releasably supporting the main section from the pit-walls, and means for releasably supporting the auxiliary section from the main table-section and one of the pit-walls.

4. In a drop pit-table, the combination of a vertically movable main table-section and a vertically movable auxiliary table-section, the main table-section comprising a rigid structure provided with rail-sections thereon of sufficient length to support one or more pairs of wheels adjacent one end of the table and one side of the pit, and with rigid side-members projecting beyond said rail-sections and extending to the other end of the table and the other side of the pit, the main section, with said projecting members, forming an open-ended space at said other end of the table and said other side of the pit, the auxiliary section, fitting in said space, being provided with rail-sections and substantially conterminous with one end of the projecting members and the open end of said space, and meeting the adjacent pit-wall so that a pair of wheels on the auxiliary section may run directly from the auxiliary section onto the adjacent side of the pit, the auxiliary section being separable from and lowerable independently of the main table section, means for releasably supporting the main-section from the pit-walls and in pit-bridging position, and means for releasably supporting the auxiliary table-section in said open-ended space.

5. In a drop pit-table, the combination of a vertically movable main table-section and a vertically movable auxiliary table-section, the main table section comprising a rigid structure provided with rails thereon of sufficient length to support one or more pairs of wheels adjacent one end of the table and one side of the pit, and provided with rigid side-beams extending across the pit and projecting beyond said rail-sections to the other side of the pit, the main section, with the projecting portions of the beams, forming an open-ended space at said other end of the table and said other side of the pit, the auxiliary section, fitting in said space, being provided with rail-sections and substantially conterminous with the projecting ends of said beams and the open end of said space, and meeting the adjacent pit-wall so that a pair of wheels on the auxiliary section

- may run directly from the auxiliary section onto the adjacent side of the pit, the auxiliary section being separable from and lowerable independently of the main table section; means for releasably supporting the main section from the pit-walls and in pit-bridging position, and means for releasably supporting the auxiliary table-section in said open-ended space.
6. In a drop pit-table, the combination of a vertically movable main table-section and a vertically movable auxiliary table-section, the main table section comprising a rigid structure provided with longitudinal beams having rail-sections thereon of sufficient length to support one or more pairs of wheels adjacent one end of the table and one side of the pit and with rigid side-beams projecting from beyond the rail-sections and extending to the other end of the table and the other side of the pit, the main section, with said projecting members, forming an open-ended space at said other end of the table and said other side of the pit, the auxiliary section, fitting in said space, being provided with rail-sections, and substantially conterminous with the projecting ends of said side-beams and the open end of said space, and meeting the adjacent pit-wall so that a pair of wheels on the auxiliary section may run directly from the auxiliary section onto the adjacent side of the pit, the auxiliary section being separable from and lowerable independently of the main table section, means for releasably supporting the main section from the pit-walls and in pit-bridging position, and means for releasably supporting the auxiliary table-section from the pit-wall and from the main section in said open-ended space.
7. In a drop table, the combination of a main table-section comprising rigidly connected side-beams for extending entirely across a pit, a cross-beam at one end of said side-beams, and a cross-beam disposed inwardly of the other end of said side-beams, the space between said inwardly disposed cross-beam and said other end of the side-beams providing a space with an open end at the other end of the main table-section, rail-sections extending over the area between the end and inwardly disposed cross-beams of the main table-section, an auxiliary table-section fitting in said open-ended space and meeting the inwardly disposed cross-beam and the side-beams, rail-sections on the auxiliary table-section for completely extending across the space between the rail-sections on the main table-section and one side of the pit, the auxiliary table section being separable from and lowerable independently of the main table section and means for releasably supporting both of the table-sections.
8. In a drop table, the combination of a main table-section comprising rigidly connected side-beams for extending entirely across a pit, a cross-beam at one end of said side-beams, and a cross-beam disposed inwardly of the other end of said side-beams, the space between said inwardly disposed cross-beam and said other end of the side-beams providing a space with an open end at the other end of the main table-section, rail-sections extending over the area between the end and inwardly disposed cross-beams of the main table-section, an auxiliary table-section fitting in said open-ended space and meeting the inwardly disposed cross-beam and the side-beams, rail-sections on the auxiliary table-section for completely extending across the space between the rail-sections on the main table-section and one side of the pit, the auxiliary section being separable from and lowerable independently of the main table section and means for releasably supporting both of the table-sections.
9. In a drop table, the combination of a main table-section comprising rigidly connected side-beams for extending entirely across a pit, a cross-beam at one end of said side-beams, and a cross-beam disposed inwardly of the other end of said side-beams, the space between said inwardly disposed cross-beam and said other end of the side-beams providing a space with an open end at the other end of the main table-section, rail-sections extending over the area between the end and inwardly disposed cross-beams of the main table-section, an auxiliary table-section fitting in said open-ended space and meeting the inwardly disposed cross-beam and the side-beams, rail-sections on the auxiliary table-section for completely extending across the space between the rail-sections on the main table-section and one side of the pit, the auxiliary table-section comprising side and cross-beams, the auxiliary table-section being separable from and lowerable independently of the main table-section, means for releasably supporting the main table-section from the pit-walls, and means carried by the ends of the side-beams of the auxiliary table, for releasably engaging the inwardly disposed cross-beam of the main table-section and the adjacent pit-walls, to support the auxiliary table-section.
10. In a drop pit apparatus, the combination of a drop table comprising a pair of table-sections, means for releasably supporting one of the sections from the pit, means for releasably supporting the other table-section in pit-bridging position, a lifting carriage movable vertically and laterally in the pit and means on, and positioned by the lateral movement of, the carriage relatively to the table, for selectively engaging and lifting both table-sections or engaging and lifting one of the sections independently of the other.
11. In drop pit apparatus, the combination of a drop table comprising a pair of table-sections, means for releasably supporting one of the sections from the pit, means for releasably supporting the other table-section in pit-bridging position, a lifting carriage movable vertically and laterally in the pit and blocks, rigid on, and movable laterally with, the carriage relatively to the table, for selectively engaging and lifting both table-sections or engaging and lifting one of the sections independently of the other.
12. In drop pit apparatus, the combination of a main table-section adapted to extend entirely across the pit, means for releasably supporting the main section from the pit, said main-section being provided with an opening therein, an auxiliary table-section fitting in said opening, means for releasably supporting the auxiliary table-section from the pit and main-table section, and means for preventing the release of the supporting means for the main section unless the supporting means for the auxiliary section is released.
13. In drop pit apparatus, the combination of a main table-section adapted to extend entirely across the pit, means for releasably supporting the main section from the pit, said main-section being provided with an opening therein, an auxiliary table-section fitting in said opening, means for releasably supporting the auxiliary table-section from the pit and main-table section, and means for preventing the release of the supporting means for the main section unless the supporting means for the auxiliary section is released.

table-section from one side of the pit and from the main-table section, and means for locking the supporting means for the main section against release, controlled by the supporting means for the auxiliary section.

5 14. In drop pit apparatus, the combination of a main table-section adapted to extend entirely across the pit, bolts for releasably supporting both ends of the main section from the pit, said main-section being provided with an opening therein, an auxiliary table-section fitting in said opening, bolts for releasably supporting the auxiliary table-section from one side of the pit and the main-table section, and means for locking the bolts for supporting the main section against release, controlled by one of the bolts for supporting the auxiliary section.

10 15. In drop pit apparatus, the combination of a drop table comprising a pair of vertically movable table-sections, means for releasably supporting one of the sections from the pit, means for supporting the other section in pit-bridging position, and a lifting carriage movable vertically and laterally in the pit, said carriage and table-sections being provided with members fixed thereto respectively, which, by the lateral movement of the carriage relatively to the table, can 10 be corelatively positioned for selectively lifting and engaging both table-sections or for engaging and lifting one of the sections independently of the other.

HUGH K. CHRISTIE. 15
